UNITED STATES PATENT OFFICE.

JESSE ALVEN JAMES VANCE, OF MOHAWK, TENNESSEE.

RAIL-JOINT.

No. 843,853.

Specification of Letters Patent.

Patented Feb. 12, 1907.

Application filed May 29, 1906. Serial No. 319,325.

To all whom it may concern:

Be it known that I, JESSE ALVEN JAMES VANCE, a citizen of the United States, residing at Mohawk, in the county of Greene and State of Tennessee, have invented certain new and useful Improvements in Rail-Joints, of which the following is a specification, reference being had therein to the accompanying drawings.

My invention relates to improvements in joints for track-rails; and it consists in the novel construction, combination, and arrangement of parts hereinafter fully described and claimed.

The object of the invention is to provide a connection of this character which will hold the meeting ends of two track-rails firmly and securely together and in alignment without the use of the usual bolts.

Further objects and advantages of the invention, as well as the structural features by means of which they are accomplished, will be made clear by an examination of the following specification, taken in connection with the accompanying drawings, in which—

Figure 1 is a top plan view of my improved rail-joint. Fig. 2 is a side elevation of the same. Figs. 3, 4, and 5 are vertical transverse sectional views taken, respectively, on the planes indicated by the lines 3 3, 4 4, and 5 5 in Fig. 1. Fig. 6 is a detail vertical longitudinal sectional view taken on the plane indicated by the line 6 6 in Fig. 1. Fig. 7 is a perspective view of the inner chair member 4 of the joint. Figs. 8 and 9 are perspective views of the outer and inner sides of one of the intermediate chair or fish-plate members, and Fig. 10 is a perspective view of the outer chair member of the joint. Fig. 11 is a detail of parts, showing the flattened portion of the brace-screws and the intermediate washer thereon.

Referring to the drawings by numeral, 1 denotes my improved joint or connection for securing the meeting ends of two track-rails 2 together and upon cross-ties 3. The rail-joint comprises an inner rail-chair member 4, an outer chair member 5, and two similar fish-plates or intermediate chair members 6. The inner member 4 is preferably about one-half the length of the members 5, 6 and is made from one piece to fit the bases, base-flanges, and web portions of the two abutting rails 2. This member 4 comprises a base 7 to engage

the bases of the rails, inwardly-extending angular portions 8 to engage the base-flanges of the rails, and upwardly-extending parallel portions 9 to engage the webs of the rails. In the portions 9 are formed alining elongated apertures 10, which register with similar apertures formed in the webs of the rails in order to receive transverse pins 11, which latter have their tapered ends seated in sockets 12, formed in the intermediate members 6, as shown in Fig. 4. Upon these portions 9 are provided longitudinally-extending tongues or ribs 13, which project outwardly and into grooves 14, formed in the members 6. Upon the center of the base 7 is provided a rectangular block or lug 15, adapted to project into alining recesses 16, formed in the ends of the rails 2, as shown in Figs. 3 and 6. This block 15 is disposed directly beneath the small space which is left between the ends of the two rails to prevent them from buckling when they expand, and in order to prevent this space from becoming filled with sand and the like I form in said block a vertical opening 17, which extends through the base 7 and has the upper portions of its side walls flared outwardly, as shown at 18. Each of the intermediate chair members or fish-plates 6 is also formed from a single piece and comprises an angular upright portion 19 and inner and outer base portions 20 21.

The inner and outer faces of the portions 19 21 are shaped to fit over and against the outer sides of the inner member 4 and of the rails 2, a suitable depression or recess being centrally located upon said faces to receive the member 4, so that the members 6 fit snugly against the rails and the inner member. The base portion 20 has its center cut away to receive the member 4, and it is about half the width of the base 7 and the rail-bases under which it projects, as seen in Fig. 5. Upon the outer faces of the portions 19 and 21 are formed at the center and adjacent to the ends of each of the members 6 integral braces or reinforcing enlargements 23, the central one of which being larger than the end ones and having two spike-receiving apertures 24, while the end ones have but one of such apertures 24. The said grooves 14 and sockets 12 are formed in the inner faces of the portions 19 of the members 6, and in said faces are also formed sockets or seats 25 to receive the tapered ends of pins 26, which latter extend

2 through transverse elongated apertures or openings formed in the webs of the rails 2. Formed in the upper portions of the braces 23 and in integral bosses 27 upon the upright portions 19 of the members 6 are square sockets 28 to receive the square ends of brace-screws 29, any number of which latter may be employed.

The outer chair member 5 is adapted to rest upon the cross-ties 3 and comprises a base 30, along the sides of which are upwardly and inwardly projecting flanges 31 to receive the base portions 21 of the members 6. Upon these flanges 31 are integral bosses 32, in which are formed circular openings 33 to receive the lower ends of the angularly-disposed brace-screws 29. Each of these screws 29 has upon its threaded portion two nuts 34 35 and an intermediate washer 36, which latter is prevented from rotating by the engagement of a flat portion of its aperture with a flat portion 37 of the screw. The screws are applied by first inserting their threaded ends in the openings 33 and then raising their pointed upper ends into the sockets 28. The lower nut 34 is then screwed down against its boss 32 until the screw forces the portion 19 of the member 6 firmly against the member 4 or the rail 2. The other nut 35 is then screwed down to force the washer against the nut 34, and thus lock the latter in position. At the proper points in the base 30 of the member 5 are formed apertures 38, which register with the apertures 24 to receive spikes 39, the latter serving to secure the joint upon the cross-ties. In the center of the upper face of the base 30 is formed a transverse groove or channel 40, which has its ends opening through the flanges 31, as shown at 41. The bottom of this groove 40 is inclined outwardly and downwardly from its center to its outer ends, as shown in Fig. 10, and its center is disposed directly beneath the opening 17 in the block 45 or lug 15 upon the bottom of the member 4, so that the sand, &c., which falls through said opening 17 may pass down the inclined bottom of the groove 40 and out of the joint in order that the rails may freely expand and contract under the action of heat and cold.

In assembling the joint the ends of the rails 2 are inserted in the opposite ends of the member 4, and the pins 11 and 26 are then inserted in their proper apertures. The two members 6 are then placed in position upon opposite sides of the member 4 and the rails 2, so that the member 5 may be slipped longitudinally upon them. The screws 29 may then be placed in position and tightened to hold the spikes 39 driven into the cross-ties, to hold the joint upon the same. It will be seen that this joint will hold the rails firmly and securely together and in alinement with each other, but at the same time permit of 65 the necessary expansion and contraction.

Various changes in the form, proportion, and minor details of construction may be made without departing from the spirit or sacrificing any of the advantages of the invention as defined by the appended claims. 70

Having thus described my said invention, what I claim as new, and desire to secure by Letters Patent of the United States, is—

1. In a rail-joint, an inner chair member, an outer chair member, and intermediate 75 chair members or fish-plates, the latter engaging said outer member and said inner member and the rails therein.

2. In a rail-joint, an inner chair member, an outer chair member, intermediate chair 80 members, and adjustable braces between the latter and said outer member.

3. In a rail-joint, an inner chair member to engage the bases, base-flanges and web portions of the meeting ends of two rails, an 85 outer chair member, intermediate chair members or fish-plates to engage said outer member, said inner member and said rails, transverse pins in said rails engaged with said intermediate members, and adjustable braces 90 between said outer member and said intermediate members.

4. In a rail-joint, an inner chair member to engage the bases, base-flanges and web portions of the meeting ends of two rails, an 95 outer chair member, intermediate chair members or fish-plates to engage said outer member, said inner member and said rails, transverse pins in said rails engaged with said intermediate members, means for permitting sand and the like entering between the ends of the rails to pass out of the joint, and tension-screws arranged between said outer member and said intermediate members. 100

5. In a rail-joint, an inner chair member to engage the bases, base-flanges and web portions of the meeting ends of two rails, an outer chair member, intermediate chair members or fish-plates to engage said outer 110 member, said inner member and said rails, transverse pins in said rails engaged with said intermediate members, an apertured block or lug upon said inner member and engaged with recesses in the ends of said rails, a transverse outlet-passage in said outer member beneath the aperture in said block, screws engaged with seats in said outer member and said intermediate member, and nuts upon said screws, substantially as described. 115

6. In a rail-joint, an inner chair member to engage the bases, base-flanges and web portions of the meeting ends of two rails, an outer chair member, intermediate chair members or fish-plates to engage said outer 125 member, said inner member and said rails, transverse pins in said rails engaged with said intermediate members, an apertured block or lug upon said inner member and engaged with recesses in the ends of said rails, a 130

transverse outlet-passage in said outer member beneath the aperture in said block, screws engaged with seats in said outer member and said intermediate member, nuts upon said screws, means for preventing said screws from rotating, and tongues upon said inner member to engage grooves in said intermediate members, the latter and said outer member having alining apertures to receive spikes or the like, substantially as described.

7. In a rail-joint, an inner chair member to engage the meeting ends of two rails, an outer chair member, and an adjustable brace between said members.

8. In a rail-joint, an inner chair member to engage the meeting ends of two rails, an outer chair member, a tension-screw between said members, and a nut upon said screw.

9. In a rail-joint, an inner chair member to engage the meeting ends of two rails, an outer chair member, an intermediate member between said outer and inner members, and an adjustable brace between the outer member and the intermediate member.

10. In a rail-joint, an inner chair to engage the meeting ends of two rails, the latter having recesses formed in their ends, an apertured block upon said member and seated in said recesses, and an outer chair member

having a transverse groove to aline with the 30 aperture in said block, for the purpose set forth.

11. In a rail-joint, an inner chair member to engage the bases, base-flanges and web portions of the meeting ends of two rails, 35 said member having alining apertures to register with apertures in said rails, transverse pins in said apertures, an outer chair member having side flanges, spike-receiving apertures, screw-receiving apertures and a 40 transverse groove upon its bottom, intermediate chair members engaged with the flanges of said outer member and with the outer faces of the inner member and the two rails, said intermediate members having 45 spike-receiving apertures, screw-receiving sockets, and pin-receiving sockets, screws engaged with the screw-receiving sockets in said outer member and said intermediate members, and nuts upon said screws, substantially 50 as described.

In testimony whereof I hereunto affix my signature in presence of two witnesses.
